(57) CLAIM

The ornamental design of a golf putter and a ball retriever,
as shown and described.

DESCRIPTION

FIG. 1 is a top rear perspective view of a golf putter with a
golf ball retriever showing my new design;

FIG. 2 is a side elevation view of one end of the putter-
retriever shown in FIG. 1;

FIG. 3 is an elevation view of the other end of the putter-
retriever seen in FIG. 2;

FIG. 4 is a rear elevation of the putter-retriever seen in the
prior figures;

FIG. 5 is a front elevation of the putter-retriever opposite to
the rear elevation in FIG. 4;

FIG. 6 is a top plan view of the putter-retriever seen in FIG.
1; and,

FIG. 7 is a bottom view of the putter-retriever seen in FIG.
1.
